UNITED STATES PATENT OFFICE.

EDWIN FORDICE, OF FAIRBURY, NEBRASKA.

SKATE ATTACHMENT.

1,141,454.

Specification of Letters Patent. Patented June 1, 1915.

Application filed April 1, 1914, Serial No. 828,774. Renewed February 15, 1915. Serial No. 8,347.

To all whom it may concern:

Be it known that I, EDWIN FORDICE, citizen of the United States, residing at Fairbury, in the county of Jefferson and State 5 of Nebraska, have invented certain new and useful Improvements in Skate Attachments, of which the following is a specification.

This invention relates to improvements in ankle brace attachments for skates, and has 10 for one of its objects to improve the construction and increase the efficiency and utility of devices of this character.

Another object of the invention is to provide a simply constructed device which may 15 be attached to a skate and automatically adjustable to the ankle of the wearer and flexibly coupled to the skate to adapt it to the movement of the skate, and the movements between the ankle joint and the skate.

20 With these and other objects in view the invention consists in certain novel features of construction as hereinafter shown and described and then specifically pointed out in the claims.

25 The improved device may be applied to various forms of skates, and it is not desired therefore to limit the invention in this respect, but for the purpose of illustration the improved device is shown applied to a 30 conventional skate, and in the drawings—

Figure 1 is a side elevation of a skate with the improvement applied. Fig. 2 is a rear elevation of the same. Fig. 3 is a detached perspective view of the improved device.

35 Corresponding and like parts are referred to in the following description and indicated in all the views of the accompanying drawings by the same reference characters.

The improved device may be attached to 40 various forms of skates and requires no change in the skate except to form an aperture through the runner 10 at the rear, preferably beneath the heelplate or clamp 11. The improved device is formed in two 45 portions, a lower portion represented conventionally at 13, and an upper portion represented conventionally at 14. The lower portion 13 of the improved device is formed with a threaded terminal 15 extending 50 through the aperture of the runner 10 and provided with nuts 16—17 bearing upon opposite sides of the runner and by means of which the member 13 is firmly clamped in position for movement laterally, while 55 at the same time will rotate freely in the runner. The lower portion 13 is preferably

circular or in rod-like form and is curved forwardly and thence upwardly to pass around the heel clamp plate 11, and is flattened at its upper portion as represented at 60 18. The member 14 is preferably in the form of a flat bar and forked at its lower end, as represented at 19, to engage over the flattened portion 18 of the lower member and pivoted thereto as shown at 19'. 65

By forming the member 13 to curve forwardly the joint 19—19' will be located directly opposite the ankle joint of the wearer and thus prevent cramping or straining of the parts when in use. By this means 70 a joint is produced between the two members which permits movement in alinement with the longitudinal plane of the runner, but is prevented from lateral or twisting movement. 75

Attached to the member 14 near its forked end 19 is a relatively wide strap device 20 adapted to engage around the ankle of the wearer, and likewise provided with a strap device 21 near its upper end adapted to 80 pass around the calf of the leg of the wearer. The member 14 is thus firmly coupled to the leg of the wearer, while the ankle joint is left free to move relative to the skate by reason of the swiveled member 13. 85

The improved device will preferably be attached to the outer sides of the runners of the skates, and will therefore be formed in rights and lefts.

The members 13—14 will be preferably 90 formed of steel as light as possible consistent with the strains to which they are subjected, and when not in use will fold into substantially parallel relation to the runner.

Having thus described the invention, what 95 is claimed as new is:

1. An attachment for skates comprising a lower member having one terminal extending at right angles thereto and adapted to be pivotally engaged through a skate runner, 100 the right-angled extension being directed forwardly and thence upwardly, an upper member pivotally united to the lower member, a band connected to the upper member and adapted to engage around the ankle portion of the wearer of the skate, and a band adapted to be engaged around the leg portion of the wearer of the skate. 105

2. An attachment for skates comprising a lower member having one terminal ex- 110 tending at right angles thereto and thence directed forwardly and upwardly and flat-

tened at its upper end, said right-angled portion adapted to be pivotally engaged through a skate runner, an upper member forked at its lower end to engage over the flattened portion of the lower member and pivotally united thereto, a band connected to the upper member and adapted to engage around the ankle portion of the wearer of

the skate, and a band adapted to be engaged around the leg portion of the skate. ¹⁰

In testimony whereof I affix my signature in presence of two witnesses.

EDWIN FORDICE. [L.S.]

Witnesses:

J. MONROE DAVIS,
J. ELBERT TOMERY.
